US00D994048S

(12) **United States Design Patent** (10) **Patent No.:** **US D994,048 S**
(45) **Date of Patent:** **** Aug. 1, 2023**

(54) **TOY GUN**

(71) Applicant: **Hong Huang**, Shantou (CN)
(72) Inventor: **Hong Huang**, Shantou (CN)
(**) Term: **15 Years**
(21) Appl. No.: **29/838,131**
(22) Filed: **May 11, 2022**

(51) **LOC (14) Cl.** **21-01**
(52) **U.S. Cl.** **USPC** **D21/572**; D21/573; D21/401

(57) **CLAIM**

The ornamental design for a toy gun, as shown and described.

DESCRIPTION

FIG. 1 is a first perspective view of a toy gun showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 1;

FIG. 11 is an enlarged view of the selected portion 11 in FIG. 2; and,

FIG. 12 is an enlarged view of the selected portion 12 in FIG. 2.

The evenly-spaced broken lines shown in the drawings depict portions of the toy gun that form no part of the claimed design; the unevenly-spaced broken lines delineate areas of the figures shown enlarged and form no part of the claimed design.

1 Claim, 12 Drawing Sheets
